GRINDING WHEEL MOUNTING

Hugo W. H. Beth, Worcester, Mass., assignor to
Norton Company, Worcester, Mass., a corpora-
tion of Massachusetts

Application January 4, 1936, Serial No. 57,622

1 Claim. (Cl. 51—209)

The invention relates to abrasive wheels and mountings therefor.

One object of the invention is to provide an abrasive wheel and mounting adapted to withstand a high degree of heat during grinding. Another object of the invention is to provide a multi-part mounting for an abrasive wheel whereby a tough, heat resistant cement may be used. Another object of the invention is to provide a stronger union between abrasive wheel and mounting under varied conditions of practical use. Another object of the invention is to provide a combined abrasive wheel and mounting construction for connection to specific spindle flanges. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claim.

In the accompanying drawing, in which is shown one of various possible embodiments of the mechanical features of this invention,

Fig. 1 is a plan view of one-half of an annular grinding wheel and mounting plate constructed in accordance with the invention;

Fig. 2 is an axial sectional view of the wheel and mounting of Fig. 1; and

Fig. 3 is an axial sectional view similar to Fig. 2 illustrating a modification of the invention, the grinding wheel being substantially a disk as distinguished from an annulus, and an additional mounting plate being provided in order to permit attachment to a pre-existing flange on a wheel spindle.

As conducive to a clearer understanding of the present invention, it is noted that there are particular grinding purposes for which a wheel grinding on a radial surface is preferred. It is often a requirement in such a grinding operation that there shall be nothing projecting beyond the plane of the grinding face in the direction away from the supporting spindle or other supporting means. To mount such grinding wheels there have been proposed hitherto both soft and hard rubber as a cement uniting the wheel to a backing plate which can be readily attached to a spindle. By soft rubber is meant a rubber vulcanized with a relatively small amount of sulphur, which rubber is reasonably resilient. By hard rubber is meant that substance sometimes called ebonite which is vulcanized with a larger amount of sulphur, usually 20% or more, and which is relatively

rigid. Hard rubber has an advantage over soft rubber, in that it has greater tensile strength, and no cement however great its properties of adhesion can be stronger than the coherence of its particles to each other. Hard rubber has the further advantage that it is less susceptible to thermal shocks, and sometimes wheels such as herein mentioned are called upon to do so much work that overheating occurs, therefore making the resistance to heat of the cement a factor of importance. On the other hand, as a steel or iron backing plate is usually used on account of its strength and other desirable qualities, and as the coefficient of expansion of steel or iron is different from that of many grinding wheels, soft rubber has the advantage that, being resilient, differences of coefficient of expansion become immaterial, while hard rubber, having no such resilient or plastic qualities, or to a lesser degree, there has been experienced rupturing of the cement in cases where the diameter of the wheel was large.

Referring now to Figs. 1 and 2, I provide a grinding wheel 10 shown as a cylindrical annulus, the radial face 11 being the grinding face. This grinding wheel 10 is to be secured to a spindle 12 having an integral disk-like flange 13 with a plurality of tapped holes 14. The spindle 12 may be mounted in any suitable bearings and rotated in any suitable manner and may be part of a complete machine, not shown. There is no particular significance to the orientation of the axis of the spindle 12 in the present drawing, and actually the spindle 12 might be inverted from the position shown, or might be horizontal, or might be positioned in any other position desired.

I provide a plurality of sectors of an annulus 15, preferably made of steel since steel provides the desired strength and is relatively inexpensive. These sectors when placed adjacent each other form a broken annulus separated by narrow spaces 16. I provide a disk 17, also preferably of steel, having an annular outer portion 18 which is thinner than the inner portion thereof 19, which portions are separated by a cylindrical shoulder 20. The sectors 15 are secured to the portion 18 and completely cover said portion except for the narrow spaces or grooves 16. The sectors 15 may be fastened to the portion 18 of the disk 17 by means of screws 21, there being counterbored holes 22 in the sectors 15. Thus the disk 17 and sectors 15 together form substantially a disk, which however is broken by the grooves 16 and by a narrow annular slot 25 between the shoulder 20 and the sectors 15. Al-

though sectors 15 are attached to the disk 17 by the screws 21, there is a certain resiliency to the screws and within the limits of expansion and contraction due to heat the sectors 15 may be said to be independent of each other.

I now secure the grinding wheel 10 to the sectors 15 by a hard rubber cement in the following manner. Sandblasting the outside of the sectors 15, I place a thin annular sheet (for example $\frac{1}{16}$ " thick) of unvulcanized hard rubber composition, being milled rubber containing 20% or more of sulphur, upon the sectors 15, and then place the grinding wheel 10 in matching relation upon the rubber, and with its outer circle coinciding with the outer circle of the sectors 15, and secure the parts together with ordinary screw clamps. I now place the clamped plate and wheel with the unvulcanized hard rubber composition between them in the vulcanizing oven and vulcanize at a temperature and for a length of time which is well understood by those cognizant with the manufacture of hard rubber, for example 14 hours at 160° C. I use a sufficient number of clamps to secure intimate union of the surfaces of the grinding wheel 10 with the rubber. Because free access is provided to the screws 21, both before and after vulcanizing, I may cement the sectors 15 to the wheel 10 prior to the attachment of the sectors to the disk 17, but the procedure first described is preferred as it is simpler.

The wheel and plate are now securely fastened together and in the cooling of the combined article from vulcanizing temperature, cracks do not appear on account of the fact that the cemented and vulcanized areas have no dimension which is so great as to create enough differential of expansion to break the rubber, at least when the article is embodied in a wheel and plate having a diameter not greater than 30" with eight sectors according to the present drawing, and a considerably larger article may be successfully made using a greater number of sectors. As previously stated, radial expansion is taken care of by relative motion at the screws 21, and the holes 22 may be slightly oversize and the screws 21 not fully tightened until after the vulcanizing operation. Even after the screws 21 are tightened, and when the wheel heats up in use, there is sufficient give and resiliency to the screws to permit the relative movement without fracture.

If the spindle 12 has a locating center projection 31, the disk 17 will be provided with a matching central hole 32. The disk 17 has counterbored holes 33 matching the holes 14 for attachment of the assembly to the flange 13 of the spindle 12. It will be understood that spindle flanges 13 are already existing and therefore, from the standpoint of the grinding wheel manufacturer, unchangeable things which are to be fitted with a mating mounting for a grinding wheel; otherwise, and in the case of sufficiently

large flanges 13 which are or can be provided with the required number of holes, the sectors 15 may be attached directly to the spindle flange 13, provided that a suitable template is provided in order to locate the counterbored holes 22 in desired position.

Referring now to Fig. 3, I have therein shown a grinding wheel 10a which is substantially a disk, having a relatively small central hole 35, and it may be understood that in some cases there will be no central hole. For the mounting of this wheel 10a which is to grind on a flat face 11a, I provide sectors 15 as described, and I may provide a disk 17 as already described for the attachment of the sectors 15 thereto. In fact the construction of all parts excepting the grinding wheel is the same as already described in the case of the embodiment of Figs. 1 and 2, excepting that the holes 14a are not tapped, nuts 14b being provided instead, in order that the wheel and mounting may be readily removed from the spindle 12. Also, in case it is desired to be able to use the disk 17 again after the wheel has been used up, without difficulty owing to inaccessibility of the screws 21, instead of providing threaded holes in the portion 18 for the screws 21, I may provide nuts 21a. The wheel 10a and sectors 15 in the embodiment of Fig. 3 may be secured together by vulcanized hard rubber cement 30a according to any of the methods already described.

While vitrified wheels may be particularly noted, the invention is likewise applicable to other types of grinding wheels, such as silicate bonded grinding wheels, cement bonded grinding wheels, rubber, shellac, and artificial resin bonded grinding wheels, and any abrasive material whatsoever may be used to form the grinding wheel.

It will thus be seen that there has been provided by this invention an article in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or illustrated in the accompanying drawing is to be interpreted as illustrative and not in a limiting sense.

I claim:—

An abrasive wheel mounting comprising a bonded abrasive wheel, a circular mounting plate for attachment to a machine spindle, means on the mounting plate for attaching the plate to said spindle in axial alignment of the plate and spindle, a plurality of sectors cemented to the back of the abrasive wheel, and means attaching the sectors to the mounting plate.
